UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

MOLDING APPARATUS.

Application filed November 5, 1921. Serial No. 512,970.

To all whom it may concern:

Be it known that I, JAMES B. LADD, a citizen of the United States of America, and resident of Ardmore, in the county of Montgomery, in the State of Pennsylvania, have invented certain new and useful Improvements in Molding Apparatus, of which the following is a true and exact description, reference being had to the accompanying drawings, which form a part thereof.

My invention relates to molding apparatus of the general type described in the patent to Lemoine No. 1,299,967 of April 8, 1919. The object of my invention being particularly to adapt mechanism of the general character of that described by Lemoine to the manufacture of molds having one plain and one bell end and in which the flasks are supported during the mold forming operation with the bell end uppermost. My object is further to adapt and improve the mechanism so that it will be adapted to simultaneously form a multiple series of molds and to rapidly and accurately shift the multiple series of flasks to and from the position in which the molds are formed.

The nature of my improvements will be best understood as described in connection with the drawings in which they are illustrated and in which—

Figure 1 is a vertical elevation taken on the section line 1—1 of Fig. 2.

Figure 2 is a vertical elevation taken on the section line 2—2 of Fig. 1 and

Figures 3, 4, 5 and 6 are respectively horizontal sections taken on the section lines 3—3, 4—4, 5—5 and 6—6 respectively.

A, A, are vertical columns firmly secured to the ground at their base and suitably braced at their upper ends as by means B, B, and C, C. The columns A are slotted at their upper ends as by turning in flanges A' A² (see Fig. 3) so as to afford guides for the head F. Lower down the slots formed by the inwardly turned flanges A' form guides for the ram head I and still lower down the columns are most conveniently made solid as indicated in Figures 5 and 6. D, D, are short beams extending between

the beams C, C and acting in connection with the adjacent beams D to support the rods E, E, to the lower ends of which are secured pistons indicated at E'. F is a head or beam having ends F' F' which are guided in the slots at the top of the columns A as shown in Fig. 3 and to which are secured the cylinders G, G, in which the pistons fit, G' G' indicating the heads of these cylinders. The cylinders G, G, are continued as indicated at G² in tubular form and secured at bottom to the ram head I and the tubular extensions of the cylinders are formed with guide rims as indicated at G³ G³. H, H, are pulleys secured to the beam or head F and H' H' are similar pulleys secured to the head J to be hereafter described, H² H² indicating ropes or chains working over the pulleys as indicated. The ram head I is through its ends I' I' guided in the slots A' of the column A and is formed with a series of vertical perforations as indicated at I² for the passage of the main ramming patterns and has attached to its lower side a series of patterns I³ I³ etc. for forming the bell mouth of the molds. J is a head guided on the guideways G³ as shown in Fig. 4 and supporting the pulleys H' and descending from this head are the main ramming patterns K, K, etc., the ramming heads of which are indicated at K'.

L is a rotatable mold rack support pivotally supported as indicated at L' L² and supporting the platforms N and N' on each side of which are formed a multiple series of racks for supporting pipe molds, the platform N having its mold supporting device N N² formed so as to engage and support the bell end of the flask and the platform N' having guiding recesses N³ formed in which to properly align the lower end of the flask. M is a cylinder in which works the piston M' having attached to it a rack M² which engages a spur gear L³ on the rotatable support L the construction being such that as the piston is reciprocated the support and racks attached to it oscillate through an angle of 180° bringing each multiple rack in turn into alignment with the mold ramming

machinery and after the ramming of the mold back to a position in which the flasks can be readily removed and replaced.

- 5   O is a ram head formed as shown with a series of apertures O' so spaced as to come into alignment with the flasks held in a mold rack when the rack is in position for ramming the molds and to this ram head and surrounding the apertures O' are attached 10 the annular rims P, P, etc. which are externally of a size to enter and fit the bottom ends of the flasks and internally of such size as to fit the ramming heads of the main ramming patterns. The ram head O is secured 15 to the top of a plunger Q working in a cylinder Q' by means of which the ramming head is elevated to engage the rims P in the flask and retracted to disengage the rims and flasks. It is desirable that the rims P should 20 move slowly upward in the flasks when the ramming heads of the main ramming patterns begin their operation of compacting the sand in the mold and for this purpose I have shown a pipe R entering the cylinder 25 Q' and having a valve R' with an operating arm R² extending from it in position to be engaged by a finger R³ on the head J the upward movement of which head draws the ramming patterns up through the molds.
- 30   S, S, etc. are the mold flasks having as shown their bell ends S' held in elevated position and their plain ends S² turned downward.
- 35   In operation a multiple series of flasks are placed in the flask rests remote from the ramming machinery and the ramming head O being in retracted position and the ramming patterns in position elevated above the flasks. The flask rack is rotated by means 40 of the cylinder M and the mechanism described through 180° to the position shown at the left hand side of Fig. 2. With the flasks in this position the ram head O is elevated with rims P, which rims enter the 45 bottoms of the flasks. The ramming patterns K, K, are lowered through the flasks to the position shown in Figures 1 and 2. The flasks are then charged with sand after which power is applied to the ropes or chains 50 H² with the effect of drawing down the head F against a constant pressure maintained in the cylinders G, G, until the attached head I with its patterns I³ are drawn down against and into the bell mouths of the 55 flasks, further application of power through the ropes H² draws up the head J and the attached ramming patterns K, K, etc. Toward the beginning of the upward movement of these patterns a further upward 60 movement is imparted to the ram head O and the rims P by the opening of the valve R' and for the purpose of insuring the compacting of the molding sand at the plain end of the flask.

65   After the ramming patterns are with-

drawn from the molds the pressure fluid in cylinders G presses these cylinders and their attached heads F and I upward so that the patterns I³ clear the tops of the flasks and then the ram head O being moved downward to disengage the rims P the rack support L is again rotated through an angle of 180° to bring the complete molds into position for ready removal and to bring a new set of flasks in position for ramming.

70   It will be observed that in my construction the mechanisms for acting upon the tops and bottom of the mold are in proper and permanent alignment with each other and in fixed and permanent operative relationship with the mechanism for transporting the molds to and from ramming position.

75   Having now described my invention, what I claim as new and desire to secure by Letters Patent, is:

80   1. A pipe mold ramming machine comprising in combination mold supporting means adapted to hold a pipe mold with its bell end uppermost, a vertically movable head perforated to give passage to a pattern head and having surrounding said perforation an annular upwardly projecting rim adapted to fit in the plain bottom end of the mold, means for advancing and re- 85 tracting said head supported independently of the mold, a socket pattern vertically movable into and out of the top of the mold, a main ramming pattern centered in its lower position in the mold by the rim and socket pattern and means for drawing the main 90 ramming pattern through the mold.

95   2. A pipe mold ramming machine comprising in combination mold supporting means adapted to hold a pipe mold with its bell end uppermost, a vertically movable head perforated to give passage to a pattern head and having surrounding said perforation an annular upwardly projecting rim adapted to fit in the plain bottom end of the mold, means for advancing and re- 100 tracting said head supported independently of the mold, a socket pattern vertically movable into and out of the top of the mold, a main ramming pattern centered in its lower position in the mold by the rim and socket pattern, means for drawing the main ramming pattern through the mold, and means operating synchronously with the upward movement of the main ramming pattern to cause the rim supporting head to move toward the mold and the rim to move upward in the mold for a short distance as the main ramming pattern begins its operation.

105   3. A pipe mold ramming machine comprising a rotatable mold supporting rack support having separate sets of racks each adapted to hold a multiple number of pipe molds with their axes parallel and in the same vertical plane, a ram located at the 110 base of the rack support in position to reg- 115

ister in turn with the racks, a ram head having annular rims extending up from it adapted to register with and enter the plain ends of the series of pipe molds supported on a rack, a ram head vertically movable above the rack and in fixed alignment with the lower ram, a series of bell mouth patterns secured to said ram head arranged to enter the bell ends of the molds when the ram head is depressed and a series of ramming patterns adapted to be drawn upward through the molds and to fit in lower position in the annular rims supported on the lower ram head. ¹⁰

JAMES B. LADD.
